UNITED STATES PATENT OFFICE.

GEORGE CLARK, OF BONDI BEACH, SYDNEY, NEW SOUTH WALES, AUSTRALIA.

APPARATUS FOR MOLDING CONCRETE WALLS IN SITU.

1,101,484.

Specification of Letters Patent.

Patented June 23, 1914.

Original application filed October 15, 1912, Serial No. 578,254. Divided and this application filed September 18, 1912. Serial No. 721,095.

To all whom it may concern:

Be it known that I, GEORGE CLARK, a subject of the King of Great Britain, residing at Bondi Beach, Sydney, in the State of 5 New South Wales, Australia, architect, have invented Apparatus for Molding Concrete Walls *in situ*.

The present application is a division of my copending application Serial No. 578,10 254, filed Oct. 15, 1912.

The following is a specification of my invention:

The object of this invention is to provide simple apparatus for use in molding concrete walls *in situ* continuously and expeditiously.

The invention is illustrated by the accompanying drawings, whereof—

Figure 1 is a perspective view of a section of concrete building showing the apparatus in position for constructing both cavity and solid walls, Fig. 2 is a detail perspective illustrating the external angle construction, Fig. 3 is a transverse section 20 through the foundation showing the means of erecting the apparatus thereon for the first course of concrete, Fig. 4 is a plan of the apparatus showing the application of the cores thereto.

The apparatus comprises mold planks C, C, adapted to be set on edge face to face at the required distance apart. These planks are provided near their lower edges and on 30 their inner or adjacent sides with laterally projecting pins C¹, which after the first course is molded rest on the preceding course of concrete, such as B or B¹ and while temporarily supporting the planks constitute the gage for the height of each 35 course. By this means the lower portion C² of the planks below the pins C¹ overlap the previously molded course of concrete on the outside.

The planks are clamped to form the mold 40 by clamping devices D comprising vertical ribs a arranged opposite each other and placed against the outside of the respective planks. Each rib of the pair extends above the top edges of the planks and is connected 45 to the other by a compression rod b adjusted by means of nuts engaging the threaded ends of said rod which pass through holes in the ribs a. By adjusting the length of the compression rod between the ribs, the grip of 50 the clamping device may be regulated.

A draw bar H is passed through slots formed in the vertical ribs at about the height of the course of concrete to be molded. Said bar is connected at one end by a pin H¹ to one rib and is provided at its other end with a cam lever d adapted to bear against a preferably flattened portion of the other rib. By operating said lever the ribs a, a, are drawn toward each other and the planks are clamped against the top of the course 60 of concrete below such as B and B¹.

Hopper boards E, provided with notches E¹ which fit over the draw bars, are placed on the top of the planks and the concrete is filled in and tamped to the level of the 70 planks, after which the hopper boards are removed and the concrete struck or leveled with the top of the planks.

Owing to foundations being usually wider than the courses, the first course is molded by 75 erecting the planks on the foundations and placing temporary spreaders S on the latter between the lower edges of the planks, as in Fig. 3. The planks are clamped by the means described and the spreaders are removed as soon as sufficient concrete is filled 80 in to maintain the planks in position.

In order to hold the planks firmly when forming an external angle, two clamping ribs a⁵ are fixed to an inner angle piece a⁶, 85 as in Fig. 2, and a comparatively short compression rod and a draw bar with a cam lever are attached thereto.

In building hollow or cavity walls, a series 90 of clamping devices are grouped together by means of adjustable distance rods g, which connect the ribs a and collapsible cores F are temporarily secured between the planks preferably by being suspended from the draw bars. To this end the latter are provided on one side with a socket e and on the other side with two clips or lugs f.

The core has a lug r on one end which fits 95 into the socket e on the draw bar of the clamping device, while on the other end are corner lugs s which rest on the clips or lugs f of the adjacent draw bar.

In using this apparatus after a certain section of one course of concrete is completed, the cores, if cavity walls are being 100 constructed, are collapsed and removed after which the clamping devices and mold planks are displaced and erected ahead for another length of work and the cores replaced on the draw bars and expanded again when the 110

process of filling and tamping is continued and so on until one complete course around the building is completed.

In providing for openings in walls, as for doors and windows, the frames thereof are fixed in position as the work proceeds and temporary relief linings are fixed between the frames and planks where necessary to block the concrete and form the mold required.

I claim:—

In an apparatus for molding concrete walls *in situ*, in combination, mold planks set on edge and adapted to overlap the sides of the previous course of concrete; clamping devices for maintaining the relation of the mold planks and comprising ribs fitted directly against the outer faces of the planks and disposed in pairs, a transverse compression rod connecting the upper ends of the ribs of each pair, a transverse draw bar con-

necting the ribs of each pair at points just above the upper edges of the mold planks, the draw bar being fixedly associated with one of the ribs and having its ends projecting through an opening in the other rib and provided with a cam latch, longitudinally disposed distance rods connecting each rib of a pair with the rib of an adjacent pair at the same side of the course, the draw bars being constructed to coact in pairs in centering and supporting a core, and cores adapted to be centered between and supported by selected pairs of draw bars and being removable from said draw bars.

In testimony whereof I have hereunto set my hand in presence of two subscribing witnesses.

GEORGE CLARK.
